UNITED STATES PATENT OFFICE.

JOHN H. WELSH, OF NEW YORK, N. Y.

AERIAL WHIRLING TOWER.

SPECIFICATION forming part of Letters Patent No. 750,140, dated January 19, 1904.

Application filed February 27, 1903. Serial No. 145,316. (No model.)

To all whom it may concern:

Be it known that I, JOHN HARRY WELSH, a citizen of the United States, of the city of New York, Coney Island, borough of Brooklyn, in the county of Kings and State of New York, have invented new and useful Improvements in Aerial Whirling Towers, of which the following is a full, clear, and exact description.

This invention relates to amusement apparatus, which from the nature of its parts may be appropriately designated as an "aerial" whirling tower; and the object that I have in view is to provide a simple and secure form of apparatus, wherein provision is made for carrying passenger-cars to a desired height above the ground and for moving said cars in a circular horizontal path during the elevation and lowering movements, whereby the cars travel in spiral paths and a good panoramic view of the locality is afforded to the passengers.

Further objects and advantages of the invention will appear in the course of the subjoined description, and the novelty will be defined by the annexed drawings.

Reference is to be had to the accompanying drawings, forming a part of this specification, in which similar characters of reference indicate corresponding parts in all the figures.

Figure 1 is a side elevation, partly in vertical section, of an amusement apparatus constructed in accordance with my invention. Fig. 2 is a sectional plan view, on an enlarged scale, through the tower, the vertically-traveling carriage, and the horizontally-rotating carrier, and Fig. 3 is a detail vertical sectional elevation showing one embodiment of means for supplying electrical energy to the motor, adapted to rotate a car-carrier in a horizontal plane. Fig. 4 is a diagrammatic view illustrating the arrangement of cables for operatively connecting the counterweight with the sliding carrier and a hauling-cable adapted to raise the sliding carrier by pulling down on the counterweight.

In carrying my invention into practice I employ a vertical tower A, which is of metallic skeletonized construction and is erected on

a suitable foundation B. The tower and the foundation may be of any approved construction known to those skilled in the art, but, as shown by Figs. 1 and 2, the tower is square in cross-section and built up of a series of corner-irons 5, each of angular form in cross-section. These angle-irons at the corner of the tower are braced or stayed by intermediate lattice-work 6, arranged in a suitable way and fastened on the several sides of the structure. The tower as a whole is anchored in place by suitable braces 7 at the bottom portion thereof and by the guy-cables 8, the latter extending from the ground to the top portion of the tower. This upper part of the tower is shown by Fig. 1 as having a series of radial arms 9, fastened in a suitable way to the tower at a point below the cap 10, the latter being surmounted by any suitable ornamentation or fixture, such as the electric lamp 11. The anchoring guy-cables 8 are fastened to the outer ends of the series of arms 9, and these arms are stayed to the cap portion of the tower by tension-rods 12.

On the tower is slidably mounted a carriage C, which surrounds said tower on the outside thereof and is adapted for movement freely in a vertical direction thereon. This carriage C is shown in the form of a track-ring 13, which is provided with inwardly-extending supports 14 in the form of lugs, that are integral with the ring 13, said lugs being disposed in pairs at the corners of the tower. These supports 14 are equipped with pairs of rollers 15 15^a, one pair of which is disposed at each corner of the tower, and said rollers are arranged, as shown by Fig. 2, for the axes 85 to lie at right angles to each other, whereby the rollers of each pair are adapted to travel on the faces of one angle-iron at the corner of the tower. It will be understood that four pairs of these rollers or their equivalents are mounted on the inner portion of the track-ring, which constitutes a part of the vertically-movable carriage C, and these rollers are arranged to ride against the outer faces of the angle-iron tower-posts, whereby the carriage 95 is limited to vertical movement on the tower,

and it is adapted to travel vertically thereon with minimum friction between the engaging surfaces. The carriage also contemplates the employment of a stay-ring 16, arranged in a 5 horizontal position above the track-ring 13 and connected rigidly thereto by a series of bolt-rods 17, said bolts being attached in a suitable way to the rings 13 and 16, both of which encircle the tower and which are 10 arranged in a parallel position. The carriage and the load sustained thereby are counterpoised by the employment of a counterweight D, arranged to travel within the limits of the tower, said counterweight being approximately 15 square in cross-section and equipped with means whereby it may travel freely against the corner-posts 5 of the tower. This counterweight is shown as having a series of rollers 18, which are mounted in suitable supports at the corners of the weight, said rollers being arranged to turn freely on horizontal axes and disposed in radial positions relatively to the counterweight, so that the rollers will ride against the inner faces of the corner- 20 posts and in the angle formed by the meeting faces of said posts. (See Fig. 2.) The employment of the rollers arranged to ride against the posts in the manner described prevents the counterweight from twisting or turning out 25 of position within the tower, and this counterweight is adapted to move with minimum friction vertically within the tower and in an opposite direction to the travel of the carriage C with its load.

30 The carriage is operatively connected with the counterweight by the employment of the series of cables 19, preferably four in number, said cables being fastened at their lower ends to the counterweight in any approved way— 35 as, for example, by the provision of an eye 20 at the center of said counterweight. The cables pass in upward directions and within the tower from the counterweight to and over guide-sheaves 21, journaled in the upper portion of 40 the tower A, and said cables thence pass in downward directions from the sheaves to the carriage C, the lower ends of said cables being fastened in a suitable way to a part of the carriage—as, for example, to the upper ring 16.

45 The weight of the carriage and its load exceeds the ponderosity of the counterweight D, and normally the carriage and the load rest at the bottom portion of the tower. I employ a suitable hoisting-motor E and a hoisting-cable 22 for the purpose of raising the carriage and its load, and in the embodiment of the invention shown by the drawings this hoisting-cable 22 passes from a suitable drum of the hoisting-engine to and beneath a guide- 50 sheave 23, anchored at the base of the tower, whence said cable 22 passes upwardly within the tower and is fastened to the bottom portion of the counterweight D in a suitable way.

The carriage is adapted to sustain a horizontal revolute carrier, on which or from which is supported a series of passenger-cars. This revolute carrier consists of inner rings 24 25 and a series of outwardly-extending arms 26, said parts being suitably connected 55 and stayed. The member 24 of the revolute carrier is fitted operatively to the track-ring 13 of the carriage, while the member 25 is disposed in like relation to the member 16 of said carriage, said carrier members 24 25 being united by stay rods or bolts 27. The base member 24 of the revolute carrier is provided with a series of sockets 28, preferably 60 four in number, and in these sockets are firmly secured the metallic arms 26 of said carrier, said arms extending tangentially from the periphery of the base member 24, as indicated more clearly by Fig. 2. The arms 26 are held firmly in place by the diagonal braces 29, and said arms are united in series by the 65 stays 30, attached to the arms at or near the outer ends thereof.

The revolute carrier is mounted on the vertically-slidable carriage to move up and down therewith on the tower, and said carrier is also capable of rotation in a horizontal plane freely around the carriage. Any suitable mechanism may be employed for imparting the desired rotation to the carrier as it travels vertically with the slidable carriage; 70 but in the drawings I have shown the apparatus as being equipped with electrically-driven means for rotating this carrier. An electric motor 31 of any suitable pattern is erected on an expanded or widened portion 75 32 of the base member 24, forming a part of the revolute carrier, and the shaft of this motor is provided with a worm 32^a, which meshes with a worm-gear 33^a, the said gear being fast with a driving-shaft 33, the latter 80 being provided with a gear-pinion 34, arranged to mesh with the teeth of an externally-geared circular rack 35, which is fastened solidly to the member 13 of the carriage. It will be seen that the electric motor 85 and the gearing are mounted on the revolute carrier to travel therewith, and the rotation of the motor-shaft operates the counter-shaft 33 to make the gear-pinion track around the circular rack 35.

90 The current of electrical energy may be supplied in any suitable way to the electric motor; but, as shown by Figs. 2 and 3, the tower is equipped with a vertical grooved conductor-base 36, the latter being secured solidly to one 95 side of the tower. In the grooves of this base 36 is provided a series of metallic conductor-rails 37, which are engaged by a series of brushes 38, attached to the under side of the member 13, forming a part of the vertically-movable carriage. The base member 24 of the revolute carrier is equipped with a series 100 of circular conductor-plates 39, which are in-

dividually engaged by the brushes 38 of the series, and to these conductor-plates 39 are electrically connected the wires 40 of the electric circuit, which includes the motor 31. 5 This construction and arrangement of conductors 37 39 and the brushes enables me to supply a current of electrical energy to the motor at all points in the vertical movement of the carriage and in the horizontal movement of 10 the carrier, whereby the motor operates efficiently to propel the carrier in a horizontal path during its vertical travel with the carrier. C. This carrier may be of any suitable or preferred construction; but it should be of such 15 strength as to sustain a series of passenger-cars F, the latter being supported by the outer ends of the arms 26. Any suitable type of car may be employed, and I prefer to suspend the cars from said arms of the revoluble carrier.

Any suitable means may be employed for illuminating the tower and the cars, and in Fig. 2 the tower is shown as equipped with a vertical conductor-base 41, which may convey 25 an electric current to the top lamp 11 and through suitable appliances to electric lamps in the cars F.

The operation of my invention will be readily understood from the foregoing description, 30 taken in connection with the drawings. The carriage C and its load exceed the weight of the counterweight D, and normally the loaded carriage has a tendency to travel downward on the tower toward the base thereof. The 35 passengers may easily enter the car F when the apparatus is lowered, and when it is desired to raise the carriage the hoisting-motor E is set in motion to wind the cable 22 on a suitable drum, thus pulling downwardly on 40 the weight D, which in turn pulls on the cables 19, so as to raise the carriage C on the tower. During the vertical travel of the carrier in an upward or downward direction the motor 31 is supplied with the current of electrical energy 45 from the conductors 37, and the rotation of this motor operates to propel the carrier in a horizontal plane, whereby the carrier is capable of moving in a spiral path, owing to its movement with the carriage and the rotary 50 movement that is imparted thereto by the motor during the vertical travel. This mode of operation gives to the passengers a good panoramic view of the locality in which the apparatus is operated.

55 It is evident that the apparatus may be equipped with any suitable means for arresting the movement of the carriage relative to the tower, and that it may also be supplied with means for controlling the motor 31 from 60 the ground, such as a starting-box in the motor-house.

Having thus described my invention, I claim as new and desire to secure by Letters Patent—

1. An amusement apparatus comprising a 65 tower, a non-revoluble carriage limited to slideable movement on said tower, a carrier revoluble on said carriage and movable vertically therewith, a counterweight slideable in the tower and connected operatively with said carriage, the aggregate weight of the carriage and the carrier exceeding the counterweight, and a hoisting mechanism connected to the counterweight and tending to pull the latter in an opposite direction against the gravity 75 of the carrier and the carriage.

2. An amusement apparatus comprising a tower, a non-revoluble carriage slideable thereon, a carrier revolably mounted on the carriage and slideable therewith, a counterweight, 80 flexible connections between the carriage and the counterweight, the aggregate weight of said carrier and the carriage exceeding the counterweight and movable by gravity to a lowered position relative to the tower, a hauling-cable attached to the counterweight, and a suitable motor or engine for pulling on the cable and the counterweight to counteract the gravity of the carrier and carriage.

3. An amusement apparatus comprising a 90 tower having a series of posts forming external track-surfaces, a non-revoluble carriage slideable relatively to the tower, rollers mounted on the carriage to turn on horizontal axes and arranged to ride against the track-surfaces of the tower-posts, said rollers being grouped in pairs at each angle of the tower, and the rollers of each pair lying at right angles to one another and disposed to ride against separate track-faces of one tower-post, a revoluble carrier on said slideable carriage, mechanism for imparting vertical movement to the carriage, and means for rotating 95 said carrier.

4. An amusement apparatus comprising a 105 tower having corner-posts of angular cross-sectional form, a slideable and revoluble carrier arranged externally on the tower, a counterweight slideable inside of the tower, rollers mounted on the corner portions of the counterweight to rotate on horizontal axes and riding against track-faces afforded by the inner angular portions of the tower-posts, flexible connections between the carriage and said counterweight, and a hauling-cable attached 110 to the counterweight.

5. In an amusement apparatus, the combination with a tower, of a non-revoluble carriage limited to slideable movement thereon, a revoluble carrier mounted on said carriage, a 120 motor carried by one of said parts, gearing between the motor-shaft and the other part, conductor-rails supported by the tower, and current-collectors carried by the carriage and frictionally engaging with the conductor-rails.

6. An amusement apparatus having a tower, a non-revoluble carriage slideable on said tower,

a carrier supported revolubly on said carriage,
an externally-toothed circular rack in fixed
relation to said slidale carriage, a motor
mounted on said carrier to travel therewith,
5 and a counter-shaft geared to the motor-shaft
and to the rack, whereby the carrier may be
rotated around the carriage.

In testimony whereof I have signed my
name to this specification in the presence of
two subscribing witnesses.

JOHN H. WELSH.
